UNITED STATES PATENT OFFICE.

FRANKLIN D. PIERCE, OF FARMINGTON, MONTANA.

BOLT-HOLDER.

No. 919,209.

Specification of Letters Patent. Patented April 20, 1909.

Application filed July 22, 1907. Serial No. 384,913.

To all whom it may concern:

Be it known that I, FRANKLIN D. PIERCE, a citizen of the United States, residing at Farmington, in the county of Teton, State 5 of Montana, have invented certain new and useful Improvements in Bolt-Holders; and I do hereby declare the following to be a full, clear, and exact description of the invention, such as will enable others skilled in the art to 10 which it appertains to make and use the same.

This invention relates to bolt holders or rather to that class of tools which are designed for holding the bolts rigid while their 15 nuts are being threaded upon them.

The object in view is to simplify and at the same time add to the efficiency of such devices and to this end one of the features of the invention lies in the provision of means 20 whereby the bolt engaging heads may be interchanged so as to hold the bolt rigid both while the nut is being screwed upon the bolt or unscrewed therefrom.

In the accompanying drawings, Figure 1 is 25 a side elevation of the device showing its manner of use, Fig. 2 is a top plan view of the device, Fig. 3 is a front elevation, Fig. 4 is a vertical longitudinal sectional view through the device, Fig. 5 is a face view of the bolt 30 engaging head employed in the application of a nut to the bolt, and, Fig. 6 is a similar view showing the character of the head used in the removal of a nut from the bolt.

As shown in the drawings the tool comprises a work engaging member and a bolt 35 engaging member and the former consists of a yoke shaped member including a connecting or body portion 10 from which extend diverging arms 11 each of these arms being 40 bent substantially at its middle to extend vertically as at 12 in spaced parallel relation. The body portion itself includes an upwardly or right angularly bent portion 13 which is parallel to the portions 12 of the 45 arms 11 but is of less height than the said portions. The portion 13 forms a collar and is provided with a threaded aperture 14 through which is adjustably engaged the shank of a threaded clamping screw 15 the 50 screw being provided at one end with a handle 16 by means of which it may be

turned. The opposite end portion of the clamping screw 15 is unthreaded as indicated at 17 to form a stud and provided with a transverse aperture 18 and this supporting 55 stud is designed for engagement in a socket 19 forming a portion of a bolt engaging head 20, the socket of this head being provided with alining openings 21 which are located diametrically opposite each other and which 60 are adapted to register with the ends of the opening 18 formed through the unthreaded end portion of the clamping screw there being a cotter pin 22 engaged through the 65 openings to hold the head in place upon the said end. The face of this bolt engaging head 20 is concaved and provided with radial teeth or serrations which bite into the head of the bolt and prevent its rotation under 70 conditions which will now be made apparent.

From the foregoing description of my invention it will be understood of course that the device is applied to the work through which the bolt is passed by engaging the vertically bent portions of the arms of its 75 yoke with one side of the work and turning the clamping screw until the bolt engaging head, which is at this time loosely engaged upon the screw, is brought to bear against the head of the bolt. The clamping screw is 80 then further turned so as to increase the pressure of the head against the bolt head and finally the pin is inserted through the socket upon the head and the unthreaded end of the said adjusting screw. The bolt is 85 in this manner securely held against turning and any tendency on its part to turn at the time of screwing the nut upon the bolt will be arrested by the biting engagement of the radial teeth upon the bolt engaging head into 90 the head of the bolt. As illustrated in the drawings I have provided two forms of such heads the one difference being however that the sharpened edges of the teeth are presented in opposite directions thus adapting 95 one head for use at the time of screwing the nut upon the bolt and the other head at the time of unscrewing the nut from the bolt.

What is claimed, is—

In a device of the character described, a 100 yoke provided with a pair of rectangularly bent ends, a stem having an arm parallel to

the end of said yoke, said arm being positioned centrally of the yoke arm and provided with a threaded aperture at the upper end, a threaded bar held in the said aperture 5 provided with a hand grip at the outer end, a bolt holding head provided with a series of radial concave teeth carried on the inner end of said bar, and a pin passing through said

head and bar to detachably connect the same.

In testimony whereof I affix my signature, in presence of two witnesses.

FRANKLIN D. PIERCE.
